UNITED STATES PATENT OFFICE.

CHARLES A. RIVERS AND FRANCIS B. STUART, OF EL PASO, TEXAS; ARA M. RIVERS
ADMINISTRATRIX OF SAID CHARLES A. RIVERS, DECEASED.

AUXILIARY-AIR-INLET SHUT-OFF VALVE.

Application filed April 7, 1919, Serial No. 288,194. Renewed January 30, 1922. Serial No. 532,899.

To all whom it may concern:

Be it known that we, CHARLES A. RIVERS and FRANCIS B. STUART, both citizens of the United States, and residents of El Paso, in 5 the county of El Paso and State of Texas, have invented certain new and useful Improvements in an Auxiliary-Air-Inlet Shut-Off Valve, of which the following is a specification.

10 This invention relates to an improved shut-off valve for the auxiliary air inlet of an internal combustion engine, and more particularly to certain improvements in a device of the character disclosed in the pending application for patent of Charles A. Rivers, Serial No. 253,841, filed September 12th, 1918.

20 The present invention has for one of its objects to provide a simple and effective auxiliary air inlet valve adapted to be operated from the dash board of a vehicle either by means of a hand actuated rod or a foot pedal to close the open end of the air inlet.

25 It is also a further general object of our invention to provide an auxiliary air inlet shut-off valve which may be easily and quickly actuated when the engine is running and the throttle closed to cut off the inlet of auxiliary air to the manifold, and which 30 may be easily and quickly applied in its operative position and is not liable to get out of order.

Having the aforementioned objects in view, the present invention comprehends 35 certain novel and improved combinations of mechanical elements, and the structural characteristics thereof, as will be more fully developed in the following description and subsequently incorporated in the subjoined 40 claims.

Figure 1 is a side elevation showing our improved shut-off valve;

Figure 2 is a top plan view showing the valve in closed position; and

45 Figure 3 is a sectional view of the end of an air inlet pipe, the standard upon which it is mounted, and the valve pivotally mounted on said standard.

50 Referring in detail to the drawings, 5 designates the auxiliary air inlet pipe which, at one of its ends, is tapped into the trunk wall of the engine manifold. The other end of this pipe is mounted upon a suitable support indicated at 6, the latter end of 55 the pipe being open to the atmosphere.

The open end of the inlet pipe 5 is mounted upon a hub 8 connected with the support or standard 6. The hub 8 is provided with an extension which is connected with a stud 10 upon which is pivotally 60 mounted the valve member 9. This valve member includes an upwardly projecting arm 11 which is formed at its lower end with a pair of wings 12 which project downwardly and laterally from the pivot 10 in 65 divergent relation to each other.

As herein illustrated, we have shown a rod 13 loosely connected at one of its ends to the upper end of the valve arm 11. This rod extends through a sleeve or other suitable guide means which may be secured in 70 the vehicle dash board.

It will be seen from an examination of Figures 1 and 2 of the drawings that when the valve member is disposed in an intermediate position, the end of the air inlet pipe 5 is open between the diverging wings 12. The operator may close the inlet pipe and shut off any communication between the open end thereof and the atmosphere by 75 either pushing or pulling upon the rod 13. If this rod is pulled, the wing 12 on the left will be moved over the open end of the pipe 5, whereas if the rod is pushed through the dash board, the right hand wing 12 will 80 be thus moved over the open end of the pipe. In either case, the admission of auxiliary air 85 to the manifold is completely cut off.

From the foregoing description, taken in connection with the accompanying drawings, the construction, method of operation and several advantages of our improved shut-off valve will be clearly and fully understood. As the valve is wholly disposed 90 exteriorly of the air inlet pipe, it will operate very freely, as its action is not liable to be impeded by foreign matter such as might possibly occur if the valve were mounted within the inlet pipe. It will also be seen that the valve member can be easily 95 applied to the end of the pipe in its operative position or removed therefrom. We have herein shown one means for applying the valve member and pivotally supporting the same, but it is manifest that 100 numerous other ways of mounting this valve might be adopted. The valve can of course be constructed in various sizes and owing to the fact that the valve member in its 105 entirety, may be stamped or cut from a 110

single metal plate, it will be appreciated that the device can be produced at relatively small cost.

The preceding description and the accompanying drawings disclose one practical embodiment of the invention, which, however, may likewise be exemplified in numerous alternative constructions. Accordingly the invention as herein claimed is to be considered as inclusive of all legitimate equivalents for the various elements employed as well as other contemplated arrangements thereof, which may satisfactorily accomplish the desired results.

15 In some makes of vehicles, it may be more convenient to apply the device on the opposite side of the engine from the arrangement illustrated in the drawing. This can be readily done in view of the fact that the 20 valve element is provided with the two diverging wings 12, the valve being operated in the same manner and with the same motion of the operating rod in either case.

We claim:—

25 1. The combination with an auxiliary air inlet for internal combustion engines connected to the engine manifold and in communication with the atmosphere at one of its ends, a valve plate placed externally of said air inlet and being arranged to move transversely across the open end thereof whereby to control the entrance of atmospheric air, said valve plate being pivoted in an intermediate position whereby it may be moved 35 in either direction to close the inlet port.

2. The combination with an auxiliary air inlet pipe for internal combustion engines connected at one of its ends to the engine manifold and in communication at its other 40 end with the atmosphere, and a valve plate placed externally of the pipe and being mounted to move transversely with respect to such pipe whereby to open and close the end thereof in communication with the atmosphere, said plate being so constructed as 45 to close the port when moved in opposite directions.

3. In combination with the intake manifold of an internal combustion engine, and 50 an auxiliary air inlet pipe connected thereto and having one of its ends normally in communication with the atmosphere, of a valve plate moving transversely across said pipe in either of two opposite directions and so 55 constructed and mounted as to close communication with the atmosphere through

such pipe but to open the communication through the pipe when the valve plate is in an intermediate position, and means for shifting said valve plate.

60

4. The combination with an auxiliary air inlet pipe for internal combustion engines connected at one of its ends to the engine manifold and in communication at its other end with the atmosphere, and a valve member pivotally mounted upon the latter end of the inlet pipe and having spaced parts operable upon a movement of the valve member in reverse directions from an intermediate position to close the end of the inlet 70 pipe and shut off communication with the atmosphere.

65

5. The combination with an auxiliary air inlet for internal combustion engines having an open end in communication with the atmosphere, of a valve member mounted for movement in either one of two directions to close the open end of the air inlet, said valve being exterior of the pipe and movable transversely across the open end thereof, and 80 means for manually operating said valve member.

75

6. The combination with an auxiliary air inlet for internal combustion engines having an open end in communication with the atmosphere, of a valve member mounted exteriorly of the inlet and movable transversely across the open end of the air inlet in either one of two directions to close the same, said inlet being open for the admission of air when the valve member is in an intermediate position, and longitudinally-movable means for manually operating said valve member.

85

7. The combination with an auxiliary air inlet pipe for internal combustion engines having an open end in communication with the atmosphere, of a valve member pivotally mounted upon said pipe and having diverging shut-off wings movable transversely across the open end of the air inlet pipe to close the same, and manually operable means connected to said member to move the same in either direction and dispose one of said wings in its closing position.

90

In testimony that they claim the foregoing as their invention, they have signed their names hereunder.

CHARLES A. RIVERS.
FRANCIS B. STUART.
